UNITED STATES PATENT OFFICE.

GEORGE C. CUMMINGS, OF ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

Application filed September 7, 1922. Serial No. 586,620.

To all whom it may concern:

Be it known that I, GEORGE C. CUMMINGS, a subject of the King of Great Britain, residing at Orange, in the county of Essex, State of New Jersey, have invented certain new and useful Improvements in Telegraph Systems, of which the following is a full, clear, concise, and exact description.

This invention relates to telegraph systems, particularly to systems equipped to provide full duplex service, but which are particularly applicable to half duplex service, that is, the transmission of signals in one direction at a time.

An object of the invention is to provide means for communicating a "break" signal to a transmitting operator upon the altering of the line condition by a receiving operator, while impulses are being repeated from one line section to another.

Another object is to insure the restoration of the equipment to normal should both the transmitting and receiving operators open the line circuits simultaneously, thereby permitting either operator to obtain control of the system.

In accordance with the above and other objects the present invention provides a pair of polarized relays associated with a line conductor in such a manner that a receiving operator may transmit a "break" signal to a transmitting operator while the latter operator is in the act of sending. Also these relays function, should the line be opened by both operators simultaneously, following the closure of the line by either operator, to restore the system to normal thereby permitting either operator to obtain control of the system.

The invention is illustrated in the accompanying drawings, in which Fig. 1 shows one embodiment of the invention; while Fig. 2 illustrates a modification of the arrangement disclosed in Fig. 1.

In Fig. 1 of the drawing are shown two terminal stations X and Y connected by a line conductor 5, and the equipment at each station when the system is used for half duplex operation. The duplex sets at each of the terminal stations X and Y have four polarized relays arranged differentially. Relays 6 and 7 are line relays, and have serially connected with line conductor 5 windings 9 and 12 respectively, while connected likewise in the artificial line AL are

windings 10 and 13. In order that the armatures of these relays may be biased, that is, arranged to remain in the position set until a subsequent energization, windings 11 and 14 are also provided. These windings are connected through a key 27 either to battery 3 or 4, depending upon the character of the bias, through an adjustable resistance 26.

A second pair of relays 15 and 16, also having three windings, are arranged to operate in conjunction with relays 6 and 7. Relay 15 may be considered a sending "break" relay, while relay 16 may be termed a transmitting or pole changer relay which applies battery to the apex of the ratio arms in which the windings of relays 6 and 7 are connected, in accordance with the message to be transmitted over the line conductor 5 to the terminal station Y and subsequently over a subscriber's circuit 18. Serially connected with the armature of relay 6 are operating windings 20 and 23 of relays 15 and 16, respectively. Normally current of sixty milliamperes flows through windings 20 and 23 and the subscriber's circuit 17 in a direction which tends to hold the armatures of relays 15 and 16 against the marking (that is, the right-hand) contacts. Batteries 31 and 33, positive and negative polarity, respectively, with their accompanying resistances 28, 29 and 30, 28 being adjustable, form a potentiometer and normally supply a current of fifteen milliamperes through windings 21 and 22 of relays 15 and 16, respectively, in a direction tending to move the armatures to their spacing (that is, their left-hand) contacts; but this current is not sufficient to overcome the effect of windings 20 and 23. Whenever the circuit of battery 33 is opened due to the separation of the armature of relay 7 from its right-hand contact, the current through the windings 21 and 22 is reversed so that it tends to hold the armatures of relays 15 and 16 against their marking contacts, but it is not of sufficient value to move them from their spacing contacts should they happen to be in engagement with the latter contacts.

Should the armatures of these relays remain in engagement with their spacing contacts until the armature of relay 7 engages its spacing (that is, its left-hand) contact, current passes through windings 19 and 24 of relays 15 and 16, respectively, and is of 110

sufficient strength to cause the restoration of these relays to their marking contacts.

Each of the relays 6 and 7 has connected between its armature and a cooperating contact a condenser 35 and a resistance 36. These elements tend to prevent any slight chattering of the armatures of relays 6 and 7, and consequent disruption of the transmitted signals which might occur due to unbalance and in addition to eliminate the sparking effects at the contacts.

At the terminal station Y there is located equipment identical to that just described as being located at terminal station X.

When it is desired to transmit impulses from the circuit 17 associated with station X to the loop circuit 18 associated with station Y, key 25 is operated whereby the battery associated therewith is disconnected from the windings 20 and 23 of relays 15 and 16, so that windings 21 and 22 of these relays move their armatures to the left. Relay 16 in thus reversing the position of its armature connects the positive source of battery with the apex of the ratio arms in which the windings of relays 6 and 7 are serially connected. An impulse will accordingly be transmitted over the line conductor 5, which traverses the windings 59, 60, 62, 63 of relays 56 and 57 in series, the greater portion of the current flowing to the negative pole of the battery through the left-hand contact of relay 66. These relays are thereupon caused to move their armatures to the right. Relay 56 in operating opens at its contact the circuit extending from the battery associated with loop circuit 18 and the windings 70 and 73 of relays 65 and 66 for causing the operation of sounder 41, which is, as is well understood by those skilled in the art, connected in operative relation with the loop circuit 18. Sounder 41 will respond in a manner to give an audible representation of the signal transmitted from the loop circuit 17 associated with station X. Relay 57 in moving its armature to the right functions to prevent the reversal of the armatures of relays 65 and 66 by windings 71 and 72 upon the opening of the loop circuit including windings 70 and 73 at the contacts of relay 56. That is, when relay 57 opens its left-hand contact the negative pole of battery 83 is disconnected from the potentiometer arrangement including resistance 78 and 79, whereby current now flows from the positive pole of this battery through resistance 79, which is of a larger value than resistance 78, and through the windings 71 and 72 of relays 65 and 66 respectively.

The direction of this current is such as to maintain the armatures in engagement with their marking (that is, their left-hand) contacts. Also when the armature of relay 57 engages its right-hand contact, a circuit is

completed through windings 69 and 74 which tends to aid windings 71 and 72.

Should the operator on the circuit 18 desire during the transmission of impulses from the loop circuit 17 to interrupt the sending of such operator, it only becomes necessary that the former operator open the transmitting key 75 for removing battery from the conductor extending to windings 70 and 73 of relays 65 and 66. Accordingly, these relays are caused to move their armatures to the right immediately upon the closure of key 25 which causes the armatures of relays 15 and 16 to move to the right, whereupon relays 56 and 57 move their armatures to the left and establish a condition in which windings 70 and 73 are effective to move their armatures to the right, the circuit of windings 70 and 73 being open at key 75 and the circuit of windings 69 and 74 being open at the right-hand contact of relay 57. The operating relay 66 causes the connection of the positive source of battery with the apex of the ratio arms in which the windings of relays 56 and 57 are included and the transmission of a corresponding impulse over line conductor 5 for likewise causing the reversal of the armatures of relays 6 and 7 and the opening of the circuit 17. Relays 15 and 16 thereupon reverse in a manner identical with that in which, as just described, relays 65 and 66 reversed when relays 56 and 57 reversed. The opening of the loop circuit 17 in this manner communicates to the operator at the station at which the circuit 17 terminates a signal indicative that the receiving operator desires to transmit.

Should the operators at the stations where the circuits 17 and 18 terminate, open their keys simultaneously, relays 15 and 16, and 65 and 66 at stations X and Y, respectively, reverse the positions of their armatures to apply spacing battery to the respective terminals of line conductor 5. The current upon being received at the stations X and Y, causes reversal of the armatures of relays 6 and 7, and 56 and 57 at stations X and Y, respectively. Relay 6 in reversing the position of its armature, opens the loop circuit 17 while relay 56 likewise opens the circuit 18 at station Y. When the armature of relay 7 engages its left-hand contact, the circuit through windings 19 and 24 is completed, the effect of which is sufficient to restore relays 15 and 16 to the position shown. Likewise, at station Y, relays 65 and 66 are caused to reverse the position of their armatures to the marking contacts. The reversal of the armatures of relays 16 and 66 at stations X and Y, respectively, impresses on the conductor 5 a marking impulse whereby relays 6 and 7, and 56 and 57 at the respective stations reverse the posi-

tion of their armatures. Circuits 17 and 18 are now closed.

Should the operator at the station to which the circuit 17 extends, close key 25 and the operator at station on circuit 18 operate key 75 as in sending, such operator will have obtained command of the circuit and can communicate with the other operator. Likewise, had the operator on the circuit 18 closed key 75 prior to the closure of the circuit 17, the other operator could have obtained command of the circuit.

From the above description, it is apparent that should both operators open their keys simultaneously the break and transmitting relays at the respective stations will be restored to normal whereby either operator may obtain control of the circuit.

In the modification shown in Fig. 2, a line conductor 101 extends between two terminating stations X and Y, where there is located duplex equipment arranged for half duplex service. Each of the terminating stations X and Y have associated therewith circuits 102 and 103 to and from which impulses are repeated. Like the arrangement described in connection with Fig. 1, a pair of relays 104 and 105 are connected with the end of the conductor 101, which terminates at station X.

Each of these relays is provided with three windings, one set of which is serially connected with the line conductor 101, while another set is serially connected with the artificial line. Likewise, the third set is connected to battery through a switch 106 and an adjustable resistance 107 for normally biasing such relays.

This modification, however, in place of employing a pair of relays having three windings as break and transmitting relays, utilizes a corresponding number of relays, but the number of windings is reduced. Windings 108 and 109 of relays 110 and 111, respectively, are connected serially with the circuit 102 through the right-hand contact and armature of relay 104. Also when the circuit is closed at key 113, current of sufficient strength flows through windings 108 and 109 to maintain the relays against their marking contacts. Also windings 114 and 115 of relays 110 and 111 are connected to resistances 116, which are adjustable, and 117 and battery 118 forming the elements of a potentiometer. These windings are supplied with current under these conditions in a direction tending to reverse the position of their armatures.

The equipment at station Y is identical to that at station X, like parts being represented with like reference characters with the prime indices added.

Inasmuch as the operation of the system, except the portion pertaining to the operation when the operators at both stations open

their keys simultaneously, is the same as described in connection with Fig. 1, a detailed description thereof is not considered necessary. The description will therefore, be confined to the operation of the system when both operators open their keys simultaneously. The operators on the circuits 102 and 103 in opening their respective keys disconnects the battery from the windings of relays 110 and 111 and 110' and 111' at stations X and Y, whereby these relays reverse the position of their armatures. A spacing impulse is thereupon transmitted over the line conductor 101 from each of the terminating stations, and therefore relays 104 and 105, and 104' and 105' at stations X and Y, respectively, reverse the positions of their armatures for opening the loop circuits extending to the respective stations. Relay 105 opens at its right-hand contact the circuit extending from battery 118 through resistances 116 and windings 114 and 115 of relays 110 and 111, respectively. However, upon the engagement of its armature with the left-hand contact, the battery which is connected to one terminal of resistance 120 is connected to the nodal point to which the battery 118 is connected. Upon the reversal of the armature of relay 110, the resistance 120 is of a much lower value than resistance 117 so that the connection of resistances 120 and 116 in the manner just described causes the respective batteries to oppose one another, whereby the current flowing through resistance 117 and the windings 114 and 115 of relays 110 and 111 is of sufficient strength to restore these relays to their marking contacts.

Likewise, at station Y relays 110' and 111' are caused to reverse the position of their armatures to the position shown in the drawing. Now when either of the operators closes his transmitting key, the other operator may obtain control of the system in a manner similar to that described in connection with Fig. 1.

Although the invention has been disclosed as applied to a particular circuit, it is obvious that changes may be made without departing from the spirit of the invention.

The invention claimed is:

1. In combination, a line extending between two stations, duplex equipment associated with said line, a circuit extending from said line at each of said stations, means for opening and closing each of said circuits, a break relay and a pole changer relay connected in each of said circuits, and circuit connections for insuring the restoration of said relays to normal following the simultaneous opening of said circuits.

2. In combination, a line extending between two stations, duplex equipment associated with said line, a circuit extending from said line at each of said stations, trans-

mitting means for opening and closing said circuits, a polarized break relay and a polarized pole changer relay connected in each of said circuits, and means for insuring the restoration of said relays to normal following the simultaneous opening of said circuits.

3. In combination, a line extending between two stations, duplex equipment connected with said line at each of said stations, 10 a circuit extending from said line at each of said stations, transmitting means individual to each of said circuits, a break relay and a pole changer relay connected in each of said circuits, and means for permitting the operator of either of said transmitting means to obtain control over said relays following the simultaneous transmission of break signals.

4. In combination, a circuit, a pole changer relay and a break relay having a plurality 20 of windings, one of the windings of each of said relays being connected serially to said circuit, a source of current in said circuit of a strength sufficient to maintain said relays in a predetermined position, a second winding 25 on each of said relays, said winding being included in a local circuit, a source of current in said local circuit of a strength tending to reverse the position of said relays, and an additional winding on each of said 30 relays arranged to aid said second mentioned winding in restoring said relays to normal under predetermined conditions.

5. In combination, a circuit, a pole changer

relay and a break relay having a plurality of windings, one of the windings of each of said relays being connected serially to said circuit, a source of current in said circuit of a strength sufficient to maintain said relays in a predetermined position, a second winding 35 on each of said relays, said winding being included in a local circuit, a source of current in said local circuit of a strength tending to reverse the position of said relays, and means included in a local circuit for insuring under predetermined conditions the restoration of 40 said relays to normal.

6. In combination, a circuit, a pole changer relay and a break relay having a plurality of windings, one of the windings of each of said relays being connected serially to said circuit, a source of current in said circuit of a strength sufficient to maintain said relays in a predetermined position, a second winding 50 on each of said relays, said windings being included in a local circuit, a source of current in said local circuit of a strength tending to reverse the position of said relays, and means effective under predetermined 55 conditions for supplying to said winding a current of sufficient strength to cause the reversal of said relays from their spacing to their marking contacts.

In witness whereof, I hereunto subscribe my name this 1st day of September, A. D. 1922.

GEORGE C. CUMMINGS.
